UNITED STATES PATENT OFFICE.

WILLIAM L. LUKENS, JOHN A. TAYLOR, AND ROBERT R. CAREY, OF BETHLEHEM,
PENNSYLVANIA, ASSIGNORS TO BETHLEHEM STEEL COMPANY, A CORPORATION
OF PENNSYLVANIA.

FUSE FOR PROJECTILES.

Application filed September 20, 1922. Serial No. 589,435.

To all whom it may concern:

Be it known that we, WILLIAM L. LUKENS, JOHN A. TAYLOR, and ROBERT R. CAREY, citizens of the United States, residing at 6 Bethlehem, Northampton County, and Bethlehem, Lehigh County, State of Pennsylvania, respectively, have invented certain new and useful Improvements in Fuses for Projectiles, of which the following is a specification.

The present invention relates to artillery ammunition and particularly to explosive projectiles having point detonating fuses of the adjustable type.

15 The object of the invention is to provide a novel and convenient fuse for use with projectiles which fuse while enclosed within the walls of the projectile is adapted to be adjusted from without, so that the battery commander or gunner may so adjust the fuse before firing that the projectile will either burst immediately upon impact of the projectile upon the target, a short interval of time after the projectile strikes the target, 20 or a short interval of time before the body of the projectile has reached the target.

25 The fuse is positioned to give the projectile a proper balance and is so designed that it does not interfere with the selection of 30 those outlines for the walls which give a minimum wind resistance.

35 In the following description and in the accompanying drawings one form of the invention is disclosed by way of example, and also modifications of certain features, but it will be understood that the invention may be modified in other ways and is not limited to those forms described and pointed out in detail.

40 In the drawings:

Fig. 1 is an axial longitudinal section through portion of a projectile having the improved fuse incorporated therewith, the movable parts of the fuse being illustrated in 45 the positions which they occupy before the projectile is fired, the fuse being adjusted to give a delayed detonation of the projectile;

Fig. 2 is a view similar to Figure 1 but 50 showing the parts in the positions which they occupy immediately after the projectile has struck its target;

Fig. 3 is a view similar to Figure 1 but showing the fuse as arranged to explode

the projectile immediately upon the impact 55 of the projectile body upon the target;

Fig. 4 is a view similar to Figures 1, 2 and 3 but showing the fuse adjusted to explode the projectile before the body of the projectile reaches the target; 60

Fig. 5 is a view similar to Figure 1 of a modified form of fuse;

Fig. 6 is a similar view of the modification but showing the parts in the positions which they occupy upon impact of the projectile; 65

Fig. 7 is a section on line 7—7 of Figure 1; and

Fig. 8 is a similar view but showing the moving parts in different positions.

The projectile body is indicated at 10, the 70 ogival nose at 11, and an adapter at 12 by means of which the body and nose of the projectile are secured together and the fuse secured in its proper position. The fuse is indicated generally at F and comprises essentially a head portion 13 and a body portion 14 having threaded engagement with each other and being in axial alignment. The outer cylindrical surface of the head 75 13 of the fuse has threaded engagement with the adapter 12, and this head portion is provided with an axial cylindrical recess therein in which are slidably contained the cylindrical primer carrier or block 15 and the cylindrical firing pin carrier or block 16, these 80 two blocks being normally locked in spaced relation by the centrifugal bolts 17 which are normally urged inwardly by springs 18. A creep spring 19 is interposed between the blocks 15 and 16 and opposes movement of these members toward each other when the bolts 17 have been withdrawn. A guide pin 20 secured in head 13 and slidably fitting within a recess in the primer carrier 85 prevents relative rotation of the primer carrier and fuse head. 90

The primer is indicated at 22 and is disposed in an axial recess in the rear end of the carrier block 15 and in position to be struck by the firing pin 23 secured to the carrier block 16. A small chamber 24, in advance of and communicating with the cavity containing the primer, contains flash powder, and leading forwardly from chamber 24 is a duct 25 having branches 26 and 27 leading in 100 opposite directions therefrom. Branch 27 communicates with a second conduit 28 leading rearwardly and opening through the rear 105

surface of the block 15. Normally a valve 29 is so adjusted that the conduit 25 is not in communication with the branch conduit 27.

5 Valve 29 is a rearwardly extending conical projection on screw plug 30 which has threaded engagement with the correspondingly threaded inner wall of an axial recess in the block 15 and opening through its 10 forward end. The stem 31 of the screw plug 30 is received within an aperture in the inner end of a stem or rod 32 and is pinned thereto. Rod 32 is arranged axially within the nose and extends forwardly 15 through an axial aperture in the point of the nose. The axial aperture is provided with slots 33 and slidably fitting within these slots are lugs 34 of an adjusting nut 35. Nut 35 has a squared aperture 36 and 20 fits closely around the squared shank 37 of rod 32. The adjusting nut 35 is maintained in the position in which it is illustrated in Figure 1 by means of a spring 38 the inner end of which presses on the adjusting nut and the outer end of which abuts against a spring retaining nut 39 secured 25 on the end of a spindle 40 projecting from rod 32.

The branch duct 26 leading from the 30 axial duct 25 in the primer carrier communicates with a chamber 41 containing a delay powder pellet, which chamber is in turn in communication with a second chamber 42 containing flash powder, and the 35 second chamber opens to the rear of the primer carrying block through an aperture 43.

The firing pin carrying block 16 supports 40 a disk 45 which disk is secured in the face of the carrier block 16, the firing pin 23 being integral therewith. Disk 45 is provided with apertures or conduits 46 leading inwardly and rearwardly and opening into an axial chamber 47 containing a magazine 45 charge of flash powder. Chamber 47 has extending rearwardly therefrom an axial channel 48 which not only passes through the rear end of the firing pin carrier block 16 but also through a transverse bottom 50 plug 49 which is threaded into the rear of the axial recess in head 13. Bottom plug 49 has a cylindrical flange 50 extending rearwardly therefrom the outer wall of this flange fitting closely against the inner wall 55 of a cavity in the forward end of base 14 of the fuse.

The cylindrical chamber within the 60 flange 50 of the bottom plug and in advance of the circular face 51 of the fuse body, contains the centrifugal shutter 52 which holds the detonating charge 53, as shown clearly in Figures 2, 4, 6, 7 and 8. Referring particularly to Figures 7 and 8 it will be seen that the shutter 52 is pivoted to 65 swing about a screw 54, between the side

wall of the containing cavity and a stop pin 55. The shutter is generally segmental in shape and is normally held in the position in which it is shown in Figure 7, by means of a spring pressed plunger 56. In such 70 position the fulminate detonating charge 53 is eccentric to the axis of the shell and not in a position to communicate with either the axial passage 48 leading forwardly to the flash powder charge 47, or with the axial 75 passage 57 leading rearwardly to the chamber 58 which contains the boosting charge of the fuse. Shutter 52 is held in this position by means of a plunger or inertia bolt 59 which is normally pressed forward 80 by a spring 60 into an aperture 61 in the rear side of the bottom plug 49. The inertia bolt 59 is also adapted to enter an aperture 62 and to lock the detonator shutter in the position shown in Figure 8, in 85 which the fuse is armed.

Normally the fuse is adjusted for delay action, as shown in Figure 1. Here, it will be seen, the valve 29 obstructs communication between branch conduit 27 and conduit 25. At the moment of firing the inertia of the moving parts of the fuse causes them to exert a force on the parts immediately in their rear during acceleration of the projectile. Thus the primer carrying block 15 90 presses against the centrifugal bolts 17 and prevents them from moving radially outwardly so long as the projectile is being accelerated, and hence prevents premature contact of the firing pin and primer and 95 explosion of the projectile. With the cessation of acceleration, however, the centrifugal safety bolts 17 fly outwardly and no longer oppose movement of the firing pin and primer carrying blocks toward each 100 other.

Initial acceleration of the projectile also causes the inertia bolt 59 to move rearwardly against the action of the spring 60 and to withdraw from recess 61. Initial rotation of the projectile occurs while pin 59 is thus withdrawn and hence the shutter or detonator carrier 52 is free to be moved laterally by centrifugal action into the position in which it is illustrated in Figure 8. 110 When this position is reached and acceleration has ceased, inertia bolt 59 moves forwardly into recess 62 and the shutter is thus locked in this position, with the fulminate charge 53 in position to be ignited by a 115 flame from the flash powder charge 47.

Upon impact of the nose of the projectile on the target the firing pin carrying block 16 flies forwardly and the firing pin 23 fires the primer 22. If the point of the 120 firing pin pierces the wall of the primer, gas will have a tendency to escape rearwardly and to prevent this the firing pin disk 45 and the primer holder 65 are provided with interlocking flanges 66 and 67 125

- respectively which prevent the rearward flow of gas from the primer at the instant of firing. Flame from the primer ignites the flash powder 24 and the flame from this 5 flash powder in turn passes through branch passage 26 and ignites the delay pellet 41. This pellet is of such composition that it burns relatively slowly and a short interval of time elapses before the flame is communicated to the flash powder in chamber 10 42. The flame then passes rearwardly and through conduits 46 to the magazine flash powder charge 47, thence to the fulminate detonator charge 53 and finally to the 15 booster charge 58. The passage 57 is provided with a gas check cup 70 and the chamber 71 in which the centrifugal shutter 52 is positioned is of such strength that the fulminate detonating charge 53 may explode 20 without causing detonation of the booster charge providing that the shutter is in the unarmed position, as shown in Figure 7. To adjust the fuse for non-delay action 25 upon impact of the shell and target, the operator grasps the adjusting nut 35 and pulls it forwardly against the action of spring 38 until lugs 34 disengage slots 33 whereupon the nut, and hence the rod or 30 spindle 32, may be rotated and the needle valve 29 moved forwardly. As a result conduit 25 is brought into direct communication with branch 27 and rearwardly extending duct 28 and the flame from the flash powder charge 24 will be instantly transmitted to the magazine flash powder charge 47, so that the projectile is exploded instantly, instead of by a delay action involving the burning of the delay pellet 41. 35 A stop pin 72 prevents outward movement of the plug 30 beyond a certain limit. To cause the projectile to burst before striking the target, the plug 30 is advanced as before by means of the adjusting nut 35 so that there is unobstructed communication 40 between flash powder 24 and the magazine charge 47. In addition the anticipator pin or sleeve 72 is fitted on to the end of the nut 35. The end of this anticipator striking the target causes the 45 primer carrying block to move rearwardly, as shown in Figure 4, causing the primer to strike the firing pin and to thereby effect the instantaneous explosion of the projectile while the body of the projectile is as yet some distance from the target. Anticipators of various lengths may be carried in quantities with the ammunition, and may be affixed whenever it is found desirable. 50 In Figure 5 the firing pin, instead of being an integral part of the disk 45' is formed separately therefrom and has an integral collar 92' clamped between the tubular member 91 which contains the 55 primer and the screw plug 91'. Forward movement of the block 16' or rearward movement of the block 15' will cause disk 45' to strike firing pin 92, shear the collar 92' and move said firing pin forwardly. The firing pin fits closely within the chamber 90 and serves to block the rearward 60 passage of gases from the primer. It will be apparent that, without departing from the spirit and scope of the invention, still other modifications may be made and the design and arrangement of 65 the component parts varied as desired. The invention is, therefore, not limited to the exact form shown and described. Having thus described the invention what we claim as new and desire to be secured 70 by Letters Patent is:
1. The combination with a hollow projectile adapted to contain an explosive charge, of an adjustable fuse entirely enclosed within the wall of said projectile, and means for effecting adjustment of said fuse from without comprising a spindle connected to the fuse and extending through an aperture in the wall of the projectile, and a nut on said spindle for turning the same and also for locking the spindle against rotation. 75
  2. The combination with a hollow projectile adapted to contain an explosive charge, of an adjustable fuse enclosed within the wall of said projectile, means for effecting adjustment of said fuse from without comprising a spindle connected to the fuse and extending through an aperture in the wall of the projectile, and a nut on said spindle and normally engaging the wall of the projectile to prevent rotation of the spindle, said nut being movable axially of the spindle to disengage the projectile wall and to permit the spindle to be 80 turned in adjusting the fuse. 90
  3. The combination with a hollow projectile adapted to contain an explosive charge, of an adjustable fuse enclosed within the wall of said projectile, means for effecting adjustment of said fuse from without comprising a spindle connected to the fuse and extending through an aperture in the wall of the projectile, and a nut non-rotatably mounted on said spindle and normally in contact with the projectile wall, the nut and wall having interengaging portions whereby said nut and hence the spindle, is normally locked against rotation, said nut being movable longitudinally of the spindle to disengage the projectile wall and to permit rotation of the spindle. 95
  4. The combination with a hollow projectile adapted to contain an explosive charge, of an adjustable fuse enclosed within the wall of said projectile, means for effecting adjustment of said fuse from without comprising a spindle connected to the fuse and extending through an aperture in the wall of the projectile, a nut slidably but 100

- non-rotatably mounted on said spindle, spring means normally holding said nut in engagement with the projectile wall, the nut and projectile having interengaging portions whereby said nut, and hence the spindle is normally locked against rotation, said nut being adapted to be moved longitudinally upon the spindle, against the action of the spring, to disengage the projectile so that the spindle may be turned, and to return to locking position when released.
5. In a fuse, the combination of a body having a head with an axial opening therein, a chamber in the body communicating with the opening, a carrier member in the forward portion of the chamber and adapted to move therein, a primer at the rear side of said carrier member, a projection carried by the carrier member and extending through said opening, a second carrier member disposed in the rearward portion of said chamber, and a firing pin at the forward side of the second carrier member, said firing pin and second carrier member being adapted to move forwardly in the chamber upon impact to engage the pin with the primer.
6. In a fuse, the combination of a body having a head provided with an axial opening, a chamber in the body communicating with the opening, forward and rearward blocks disposed in the chamber and capable of movement with respect thereto, a projection carried by the forward side of the forward block and extending through said opening, a primer carried by the rearward side of the forward block, a firing pin carried by the forward side of the rearward block, anti-creeper means disposed between the blocks, and means for spacing the blocks and responsive to centrifugal force to move outwardly to permit relative approaching movements of the blocks.
7. The combination with a projectile having an impact fuse therein, of an anticipator provided with an axial recess at one end to receive a fuse part, said anticipator extending through an aperture in the projectile point and capable of rotation with respect thereto, and releasable locking means for preventing rotation of the anticipator with respect to the projectile.
8. The combination, with a hollow projectile adapted to contain an explosive charge and having an aperture at its point, of a fuse within the projectile comprising a head portion having an opening therein, and control means for the fuse extending through the opening in the head portion and through the aperture.
9. The combination, with a hollow projectile adapted to contain an explosive charge and having an aperture at its point, of a fuse within the projectile comprising a head portion having an opening therein, control means for the fuse extending through the opening in the head and through the aperture, and an anticipator detachably connected with respect to the control means and extending forwardly of the point of the projectile.
10. The combination with a hollow projectile adapted to contain an explosive charge, of an adjustable fuse entirely enclosed within the wall of said projectile, means for changing from without the action of said fuse from delay to non-delay, or vice versa, comprising a spindle connected to the fuse and extending through an aperture in the wall of the projectile, and an anticipator adapted to be secured to said spindle.
11. The combination with a hollow projectile adapted to contain an explosive charge, of an adjustable fuse entirely enclosed within the wall of said projectile, and means operable externally of the projectile for changing the action of said fuse from delay to non-delay, or vice versa, comprising a spindle connected to the fuse and extending through an aperture in the wall of the projectile.
12. In a fuse, the combination of a head member having a longitudinal bore, a primer carrier arranged at the forward portion of the bore, a firing pin carrier arranged at the rearward portion of the bore, a primer charge carried at the rear side of the primer carrier and in alignment with the firing pin, slow and quick action flashing means carried by the primer carrier and including passageways communicating with the primer charge, a valve for opening and closing the passageway of the quick action flash means, said valve being carried by the primer charge carrier and extending beyond the forward end thereof, and means for spacing the carriers and responsive to centrifugal force to allow one carrier to move toward the other.
13. In a fuse, the combination of a head member having a longitudinal bore, a primer carrier arranged at the forward portion of the bore, a firing pin carrier arranged at the rearward portion of the bore, a primer charge carried at the rear side of the primer carrier and in alignment with the firing pin, slow and quick action flashing means carried by the primer carrier and including passageways communicating with the primer charge, a valve having a threaded connection with respect to the primer carrier and movable with respect thereto to open and close the passageway of the quick action flash means, said valve having a projection extending beyond the forward end of the fuse, and means for spacing the carriers and responsive to centrifugal force to allow one carrier to move toward the other.
14. The combination with a hollow projectile, of a fuse completely enclosed by the projectile and including a head member hav-

ing a longitudinal bore, a primer carrier arranged at the forward portion of the bore, a firing pin carrier arranged at the rearward portion of the bore, a primer charge at the rear side of the primer carrier and aligned with the firing pin, quick and delay action flash charge means carried by the primer carrier and including passageways, a valve for opening and closing the passageway 10 of the quick action flash means, said valve being carried by the primer charge carrier and having a projection extending forwardly thereof, a stem connected to the valve projection and extending through the nose end 15 of the projectile, means carried by the stem and accessible exteriorly of the projectile whereby the stem may be operated to open or close the valve, and means for spacing the carriers and responsive to centrifugal 20 force to allow one carrier to move toward the other.

15. The combination with a hollow projectile, of a fuse completely enclosed by the projectile and including a head member having a longitudinal bore, a primer carrier arranged at the forward portion of the bore, a firing pin carrier arranged at the rearward portion of the bore, a primer charge at the rear side of the primer carrier and aligned with the firing pin, quick and delay 25 action flash charge means carried by the primer carrier and including passageways, a valve for opening and closing the quick action flash passageway, said valve being threaded to the primer carrier and having a projection extending forwardly of the fuse, a stem connected to the projection and extending through a recess at the nose end of 30 the projectile, a releasable interlocking connection between the projectile and the stem, means for releasing the interlocking connection and for turning the stem to open or 35 close the valve, and means for spacing the 40

carriers and responsive to centrifugal force to allow one carrier to move toward the other.

16. In a fuse, the combination of a head member having a longitudinal bore, a carrier in the bore, a primer charge at the rear side of the primer carrier, a flash charge 50 carried by the carrier forwardly of the primer charge, two passageways in the carrier communicating with the flash charge and leading to the rear face of the carrier, a delay charge in one of the passageways, 55 a valve for opening and closing the other passageway, a second carrier in the bore and behind the first carrier, a firing pin carried by the second carrier and in alignment with the primer charge, and passageways in the second carrier in opposed relation with respect to the passageways in the first carrier.

17. The combination, with a hollow projectile including detachable hollow body and nose portions and the nose portion having an opening at its point, of a fuse disposed in the projectile and having a control member at the forward end thereof, and means extending through said opening and connected to the control member.

18. The combination, with a hollow projectile including separate hollow body and nose portions connected by an interior threaded ring and the nose having an opening at its point, of a fuse of the delay and quick action type supported by the ring interiorly of the projectile, and means extending forwardly of the fuse and through said opening for setting the fuse for delay or 80 quick action.

In testimony whereof we hereunto affix our signatures.

WILLIAM L. LUKENS.
JOHN A. TAYLOR.
